US0D1044138S

(12) **United States Design Patent** (10) **Patent No.:** **US D1,044,138 S**
(45) **Date of Patent:** **** Sep. 24, 2024**

(54) **NOSE MASK**

(71) Applicant: **Shirley Doloris Stradford**, Culver City, CA (US)

(72) Inventor: **Shirley Doloris Stradford**, Culver City, CA (US)

(**) Term: **15 Years**

(21) Appl. No.: **29/926,478**

(22) Filed: **Jan. 30, 2024**

(51) **LOC (14) Cl.** **29-02**

(52) **U.S. Cl.**

USPC **D29/108; D24/110.1**

(58) **Field of Classification Search**

USPC D29/100, 102, 105, 106, 107, 108, 110, D29/122; D2/878, 880, 881; D24/110.1

CPC A42B 5/00; A42B 3/18; A42B 3/20; A42B 1/046; A63B 71/08; A63B 71/10; A63B 71/105; A61F 9/04; A61F 9/06; A61F 9/029; A41D 13/11; A41D 13/1107; A41D 13/1161; A41D 13/1169; A41D 13/1176; A41G 7/00; A41G 7/02

(57) **CLAIM**

The ornamental design for a nose mask, as shown and described.

DESCRIPTION

FIG. 1 is a front perspective view of a nose mask showing my new design;

FIG. 2 is a rear perspective view of the nose mask;

FIG. 3 is a bottom view of the nose mask;

FIG. 4 is a top view of the nose mask;

FIG. 5 is a front view of the nose mask;

FIG. 6 is a rear view of the nose mask;

FIG. 7 is a right side view of the nose mask;

FIG. 8 is a left side view of the nose mask; and,

FIG. 9 is a perspective view of the nose mask, shown in a used condition on a human figure in broken lines.

The broken lines shown are for illustrative purposes only and form no part of the claimed design.

1 Claim, 6 Drawing Sheets
